UNITED STATES PATENT OFFICE

CLINTON F. SHADLE, OF INDIANAPOLIS, INDIANA, ASSIGNOR TO AIR DEVELOPMENT COMPANY, INC., A CORPORATION OF NEW YORK

APPARATUS FOR CONDITIONING AIR

Application filed February 11, 1929. Serial No. 339,056.

This invention relates to a process and apparatus used in connection therewith, for conditioning air, and is particularly adapted for conditioning air used in connection with 5 pneumatic brake systems for railway equipment.

The principal object of the invention is to so condition the air as to cool, clean and dry it to a certain degree by the elimination of a 10 substantial quantity of the moisture normally contained therein, and with said moisture eliminate lubricating oil, dust and the like. In this connection the invention is particularly useful as applied to air brakes for rail- 15 way trains in that great difficulty is normally had by the accumulation of water or moisture in the air brake system, which interferes with proper action of the triple and other valves and brake mechanism.

20 One feature of the invention resides in the application of the apparatus and process to train equipment and particularly locomotives wherein the apparatus employed is of simple and compact construction, installed and used 25 on the present type of locomotives for accomplishing the desired purpose.

Another feature of the invention resides in the process of conditioning air by employing natural cooling mediums, such as cold atmos- 30phere in the winter and the locomotive feed water in the summer, whereby such cooling medium is so manipulated as to be most effi- 35cient in its cooling action and thereby cause a sufficient precipitation of the moisture from the air being conditioned, together with the 40 lubricating oil and dust which will be carried away thereby.

Another feature of the invention resides in the construction and arrangement of the apparatus for so manipulating the air to be conditioned passing therethrough, and the cooling medium as to cause the conditioning action as above set forth in the most efficient manner 45 within a minimum of space.

Other features of the invention will be more fully set forth hereafter, particularly in respect to the arrangement and construction of the fins and separators, the drainage system 50 of the precipitated moisture and the means

for effecting the cooling of the air by readily available means.

The full nature of the invention will be more clearly understood from the accompanying drawings and the following description and claims: 55

Fig. 1 is a diagrammatical illustration of the application and mounting of the device on a locomotive. Fig. 2 is a central vertical section taken through the conditioner. Fig. 60 3 is a central horizontal section taken there- 65 through. Fig. 4 is an enlarged view through a central vertical section showing a portion of the conditioner as illustrated in Fig. 2. Fig. 5 is an enlarged view of a central hori- 70 zontal section showing a portion of that sec- 75 tion illustrated in Fig. 3. Fig. 6 is a section taken on the line 6—6 of Fig. 4. Fig. 7 is a section taken on the line 7—7 of Fig. 5. Fig. 8 is a section taken on the line 8—8 of Fig. 7. Fig. 9 is a section taken on the line 9—9 of Fig. 7. Fig. 10 is the same as Fig. 2 showing the application of the feed water cooler system. 80

In the drawings there is shown diagram- 75 matically a locomotive 10 having an air reser- 80voir 11, a feed water pump 12, a water cist- 85ern 13 in the tender 14, and an air com- 90pressor 15. The conditioner as herein shown is suitably located on the side of the loco- 95motive as indicated at 16. For winter use, there is an air pipe 17 leading from the air com- 100pressor 15 to the inlet of the conditioner. The outlet of the conditioner is connected with the air pipe 18, which leads to the main air reservoir 11, from which the conditioned air is delivered in the usual manner to the air brake system. When used in the summer time, or in warm climates, the conditioner is connected in the water line 19 leading from the cistern 13 to the feed water pump 12 and becomes a part thereof.

The conditioner comprises an elongated tank 20 which is substantially rectangular in cross section having an intake head 21 95 and an outlet head 22 bolted on opposite ends thereof. Mounted within said tank and ex- 100tending through the upper and lower walls thereof, there are a plurality of vertically positioned heat-radiating tubes 23, which

tubes are formed of metal having a maximum coefficient radiation. Each of said tubes is open to the exterior of the tank and separates the tank into a plurality of closed chambers or passageways 24. The interior of the tank is cooled by a suitable cooling medium such as air, water or any desired refrigerant passed through the tubes 23.

As shown herein in Figs. 1 to 9, inclusive, 10 air is used as a refrigerating medium wherein the season is such as to provide a cold atmosphere. As shown in Fig. 10, the cooling medium applied comprises feed water from the cistern of the locomotive which is 15 of a lower degree of temperature than the atmosphere, which is applicable to the device in the warmer season or in warm regions. For certain purposes, in application of the invention, suitable refrigerating units may 20 be substituted for the air cooling louvers or the water jackets. The cooling medium is caused to pass through the tubes 23.

As herein shown there are a plurality of louvers 25 having an enlarged open flared 25 end 26, which louvers are mounted preferably above the tank and terminate at the rear of the sectional units thereof, whereby air will be caused to flow therethrough when the locomotive is in motion and cause 30 a current of such air to pass downwardly through the tubes 23 and be discharged rearwardly from the lower discharge louvers 27 which have their discharge ends opening rearwardly.

35 As illustrated in Fig. 10, wherein water is employed as a cooling medium, there is a closed water jacket 125 mounted above the tank, into which water passes from the cistern, and is thereby caused to pass directly 40 through the tubes 23 into the lower water jacket 127 from whence it passes to the feed water pump. Thus, water is circulated between the cistern and the feed water pump through the radiating tubes 23.

45 The air to be conditioned is caused to circulate through the tank between the cooling or radiating tubes 23. The air is introduced from the compressor 15 under high pressure of about ten atmospheres to the inlet connection 28 in the inlet header 21. The air thereupon engages with a group of separators 29 mounted in the front of the tank as illustrated in Figs. 7 and 8. Said separators comprise a plurality of trough-like baffles 30, 50 V-shaped in cross section and mounted vertically in the front end of the tank with the vertex of the V section extending forwardly and having the rearwardly extending edges thereof curved forwardly to provide troughs 31. Said separators are herein shown, as in 55 Fig. 7, mounted in three rows and in staggered relation with respect to each other so that the air passing therethrough will be separated and entrapped in the troughs 31 which 60 will result in the removal and separation of

lubricating oil, dust or any other foreign matter to a degree.

The separated matter will be carried by the separators to the bottom of the tank where it will be washed and drained away by the precipitated moisture. The air will then pass into that portion of the tank embodying the cooling tubes so that the temperature of the air will be reduced, thereby causing a certain amount of moisture precipitation.

As shown in Fig. 5, there are a plurality of fins 32 upon which are formed or mounted a plurality of U-shaped gutters 33, said fins are secured to the sides of the tubes in groups and in staggered relation, and the gutters are so formed in turn as to entrap the air and allow moisture and foreign matter to be deposited thereon so as to be carried thereby to the bottom of the tank and drained away. On the inner side walls of the tank there are provided a plurality of independently mounted fins 34 which angle inwardly and have their outer edge provided with vertically extending gutters 35 for likewise entrapping the moisture and foreign matter, thus facilitating its removal from the air. In the bottom of the tank there are provided a plurality of horizontally extending gutters 36 (Fig. 4) which prevent a layer of dead air from lying on the bottom of the tank and again absorbing the precipitated moisture, the air passing over the lower part of the tank being agitated by the gutters 36, which act to relieve it of moisture and foreign material while at the same time, effecting a reservoir and drainage for the moisture precipitated from the upper stratus of the air.

As shown in Fig. 6, the corners of the gutters 36 are cut away as indicated at 37 on both ends thereof, which permits the drainage to flow to the end of the section and be drained therefrom by the drainage pipes 38 communicating with both sides thereof adjacent the bottom and the cut away portions of the gutters.

As shown herein, the tank is divided into three sections or units, all of which are provided with similar interior construction as above described, there being a set of separators 29 positioned intermediate of said units and at the front thereof. Also the drain pipes 38 communicate with the lower portion of each end of said units and on each side thereof so as to permit ready drainage and removal of the moisture and foreign matter carried from the air thereby.

The invention claimed is:

1. An air conditioner of the character described including an elongated tank through which air is adapted to pass, a plurality of tubes extending across said tank in communication with the exterior thereof, a plurality of intake louvers mounted exteriorly of said tank on one side thereof and having a flared open end communicating with said tubes for

- directing air therethrough and discharging louvers mounted on the opposite side of said tank having an open discharge end in reversed position to effect a draft for facilitating the drawing of air through said tubes, whereby said tubes will be cooled by the air passing therethrough and be so positioned within said tank as to intercept and cool the air passing through said tank.
2. An air conditioner of the character described including an elongated tank through which air is adapted to pass, a plurality of tubes extending across said tank in communication with the exterior thereof, a plurality of zig-zag baffle plates mounted on the sides of said tubes for directing the air in a sinuous path past said tubes, hook shaped baffles mounted on said plates, and means mounted exteriorly of said tank in position to cause a cooling medium to pass through said tubes from one side of the tank to the other, said tubes being so positioned within said tank as to cool the air passing therethrough.
3. An air conditioner of the character described including an elongated tank through which air is adapted to pass, a plurality of tubes extending across said tank in communication with the exterior thereof, zig-zag plates secured in staggered relation to the sides of the tubes, and gutters formed on said plates for intercepting and discharging moisture and foreign elements from the air passing therewith.
4. An air conditioner of the character described including an elongated tank through which air is adapted to pass, a plurality of tubes extending across said tank in communication with the exterior thereof, a plurality of zig-zag plates mounted within said tank on the sides of said tubes, said plates extending in the general direction of flow past the tubes, with lateral offsets from one row of tubes to the next, gutters formed on said plates for catching the moisture and foreign matter precipitated from the air directed therewith, and means mounted exteriorly of said tank in position to cause a cooling medium to pass through said tubes from one side of the tank to the other, said tubes being so positioned within said tank as to cool the air passing therethrough.
5. An air conditioner of the character described including an elongated tank through which air is adapted to pass, a plurality of tubes extending across said tank in communication with the exterior thereof V-shaped baffle plates extending across the intake end of said tank in staggered relation for intercepting and distributing the air passing therethrough, means on said baffles for catching and discharging any free moisture and foreign elements contained in the air, and means mounted exteriorly of said tank in position to cause a cooling medium to pass through said tubes from one side of the tank to the other, said tubes being so positioned within said tank as to cool the air passing therethrough.
6. An air conditioner of the character described including an elongated tank having a plurality of sections through which air is adapted to pass, a plurality of tubes extending across said tank in each of said sections and in communication with the exterior thereof, means for passing a cooling medium through said tubes, a plurality of baffle plates for intercepting and distributing the air positioned at the forward end of and intermediate said sections, means on said baffle plates and in the bottom of said sections for receiving and draining precipitated moisture and foreign elements from the air, and discharge conduits connected with each side of said tank intermediate said sections and adjacent said baffle plates.
7. An air conditioner of the character described including an elongated tank embodying a plurality of sections through which air is adapted to pass, a plurality of tubes extending across said tank in each of said sections and communicating with the exterior thereof, an intake louver for each section of said tank mounted exteriorly thereof, a discharge louver for each section of said tank mounted substantially opposite to the intake louver, said intake and outlet louvers of each section being in communication with the tubes of said section whereby the tubes of each section will be independently cooled by the air directed therethrough by said louvers and positioned in the respective section of said tank to intercept and cool the air passing therethrough.
- In witness whereof, I have hereunto affixed my signature.
- CLINTON F. SHADLE.
